UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

SHOCK ABSORBER FOR PAPER CARRIAGES.

Application filed September 13, 1923. Serial No. 662,447.

My invention relates to tabulating means or equipment for adding machines and the like, and more particularly to that type of machine in which the paper carriage is propelled from one columnar position to another under the impulse of a motor, usually a spring motor.

The main objects of my invention are to provide a simple and improved cushioning mechanism for absorbing the shock or relieving the force of the impact of a tabulator dog or pawl on the paper carriage against an arresting or stop member; to employ a cushioning device in the form of an air dash-pot mounted on the paper carriage and having simple and effective connections to the tabulating stop mechanism on the paper carriage, and to design the cushioning attachment so that it may be readily applied to machines now on the market and in use without materially changing the construction of the machine or interfering with the operation of its parts.

With the above and incidental objects in view, the invention consists in certain novel features of construction and combination of parts, the essential elements whereof are recited in the appended claims, and a preferred form of embodiment of which is described in detail hereinafter and illustrated in full in the accompanying drawings, which form part of this specification.

Of said drawings, Fig. 1 is a rear elevation (foreshortened) of an adding machine, with the attachment embodying my invention applied and with the dash-pot in section to expose its construction more clearly to view, the parts being shown in their normal condition of rest; Fig. 2 is a somewhat similar view with part of the paper carriage broken away and most of the machine proper broken away, and showing the parts in the positions which they assume during movement of the paper carriage from one columnar position to another; Fig. 3 is a detail left-hand end view, showing my attachment applied to the paper carriage; and Fig. 4 is a top plan view of my attachment, with the dash-pot and the supporting end of the bracket in section.

For the sake of illustration, I have shown my invention applied to the well-known Burroughs adding machine, but it will be understood that use of the invention is not limited

thereto as it is equally applicable to other types of machines. Referring to Fig. 1 of the drawings, the reference numeral 5 designates, generally the base plate or frame of the machine and 6 the back plate or panel hinged to the base frame. Mounted on the back panel is the customary carriage track 7 upon which the shiftable paper carriage, designated generally by the reference numeral 8, is adapted to travel. The paper carriage is shifted from left to right (as viewed in Figs. 1 and 2, that is from the rear) from one columnar position to another, under tension of a spring drum 9 through its tape 10, which is fastened at 11 to the carriage frame. The carriage may be moved in the opposite direction against tension of the spring drum in any suitable manner, but is here shown as being returnable by hand. A rock shaft 12 is mounted in the carriage to support the usual tabulator or columnar stops or dogs 13, which are manually adjustable on the shaft in a manner well understood in the art. These stops 13 are adapted to cooperate or abut against a shoulder 15 on a stop bar 16, fast on the back panel 6. As is customary in the Burroughs adding machine, a slide bar 17 is reciprocated vertically upon each operation of the machine through suitable connections to the main rock shaft of the machine, to elevate a pawl 18, which coacts with the particular columnar or tabulator stop 13 in engagement with the shoulder 15 of the stop plate 16, to disengage the same and permit the carriage to be moved to its next or selected columnar position by the spring drum, the carriage being then arrested in such position by engagement of the corresponding tabulator stop 13 against the shoulder 15.

The shaft 12 in the present invention is slidably mounted relatively to the carriage frame and is connected to the cushioning device, to be described presently, in such a manner that after the shaft 12 has been arrested by engagement of one of its tabulator stops 13 with the shoulder 15 of the stop plate 16, the carriage is permitted to move slightly further toward the right (Figs. 1 and 2), the cushioning device being effective during this additional movement of the carriage to absorb the shock due to the impact of the tabulator stop 13 on the shaft 12 against the stop plate 16 and to gradually

slow up the movement of the carriage and finally arrest it in its predetermined position, unaccompanied by any vibration or recoil of the carriage. To this end, the shaft 5 is provided with extended reduced portions 20 which are formed by grooves and project through slots or apertures in the side plates 21 and 22 of the paper carriage frame.

On the right-hand extension of the shaft 10 12 is an adjustable dog 23 having a forwardly extending extension 24 contacting with and projecting into the path of movement of the lower arm of a lever 25, which is pivoted on a stud 26 (Fig. 3) projecting rearwardly 15 from a bracket 27 and is retained on the stud by the head of a screw 28. The bracket 27 is supported on the right-hand end of the carriage, the bracket being provided with two forwardly projecting lugs 27^a and one 20 rearwardly projecting lug 27^b provided with apertures through which project the outer threaded reduced ends of three collars or posts 31 which have their opposite ends reduced and screw-threaded through the side 25 plate 22 of the carriage and into the casting of the carriage, the bracket being retained on the posts 31 by means of nuts 30 screwed onto the outer ends of the posts 31. The outer end of the bracket 27 is bent at right 30 angles to form a rearwardly extending arm, 27^c provided with an aperture through which a threaded stud 32 on the closed end of a dash-pot cylinder 33 projects, the cylinder being retained on the arm by a 35 nut 34 and washer 35. The upper end of the lever 25 is pivoted to one end of a link 36, the opposite end of which is pivoted to a forked bracket 37 mounted within and secured to the head of a cup-shaped piston or 40 plunger 38 of the dash-pot. The head of the cylinder 33 is provided with a small hole 39, the passage of air therethrough being regulated by an adjustable screw 40. As 45 best shown in Fig. 3, the lower arm of the lever 25 is so bent or offset forwardly that it is adapted to cooperate with the arm 24 of the dog 23 and the upper end of the lever is offset rearwardly to accommodate its connection to the link 36. A spring 42 is 50 connected at one end to a pin 43 on the lever 25 and at its opposite end to a pin on the bracket 27.

From the above description, it will be obvious that when a columnar dog 13 is disengaged from the shoulder 15 of the stop plate 16, during an operation of the machine, the spring drum 9 shifts the carriage toward the right, as viewed from the rear, to its next or selected columnar position, being arrested in 55 such position by engagement of the proper columnar stop 13 with the shoulder 15 on the stop plate 16. When the columnar stop 13 is disengaged from the shoulder 15, the spring 42, which is weaker or of lesser tension than the spring of the spring drum 9,

rocks the lever 25 counterclockwise, as viewed in Figs. 1 and 2, from the position shown in Fig. 1 to the position shown in Fig. 2, in which latter position the lever is arrested by engagement with a stop pin 44 projecting from the bracket 27. This movement of the lever 25 moves the piston 38 toward the left and the lever 25 through the cooperation of its lower arm with the dog 23 slides the tabulator stop shaft 12 toward the right, and relative to the carriage frame, the reduced portions 20 of the shaft being slidably mounted in the side plates of the carriage frame. During the last increment of movement of the carriage to its next or predetermined columnar position, under the influence of the spring drum 9, the proper tabulator stop 13 engages the shoulder 15, whereupon further movement of the tabulator stop shaft 12 is arrested, but movement 80 of the carriage towards the right, as viewed from the rear, is continued in opposition to the action of the spring 42 and the dash-pot. The first effect or result of the impact of a tabulator stop 13 with the shoulder 15 is to compress the air in the dash-pot cylinder, the piston being moved toward the right, but this does not result in any rebound or recoil action of the carriage or of the movable cushioning parts, as the aperture 39 in the cylinder 33 is sufficiently large to permit the air to escape from the cylinder, thus counteracting or offsetting any tendency of the piston to rebound or recoil. As the air is being compressed, it is gradually expelled through the aperture 39, thereby gradually slowing up the movement of the carriage and finally arresting it in predetermined position and thus eliminating any back and forth vibration of the carriage. The piston 38 contacts, without jar, with the end of the cylinder of the dash-pot when the carriage reaches its exact predetermined position and at the same time the shoulder, comprising the right-hand sides of the grooves forming the reduced portions 20 of the tabulator stop shaft, engage the carriage plate 21 and retaining latch 45 on the carriage plate 22. 100

As the tension of the spring 42 is less than that of the spring of the spring drum 9, it will be manifest that the carriage will be maintained in its proper columnar position by the spring drum, and that when a columnar stop 13 is rocked out of engagement with the shoulder 15 on the stop plate 16, the spring 42 moves the piston 38, lever 25 and shaft 12 to the positions shown in Fig. 2. It will also be clear that the adjustable screw 40, which carries a lock nut 41, is provided to control the rate at which the air is dispelled from the dash-pot, the space between the end of the screw and the end of the aperture 39 being increased or decreased according to the extent of cushioning effect required. 115 120 125 130

It will now be evident that my invention is admirably adapted to perform the functions primarily stated. The dash-pot absorbs the initial shock due to the impact of a tabulator stop against the stationary stop, and gradually, but without loss of time and unaccompanied by any rebound or recoil, brings the carriage to its exact predetermined position, while at the same time the mechanism is extremely simple, highly efficient, practically noiseless, and readily adapted to commercial machines now on the market and in use. As above described, the attachment, comprising my invention is readily applied to one side of the paper carriage and the dash-pot piston is connected to the tabulator stop shaft through simple connections, without necessitating any material change in the parts of the machine to accommodate the attachment.

It is to be understood that the embodiment of the invention described is susceptible of various modifications without departure from the scope or spirit of the invention, as defined in the appended claims.

I claim:

1. In a machine of the class described, the combination of a frame, a laterally shiftable paper carriage on the frame, a shaft 30 slidably mounted on said carriage, a tabulator stop on said shaft, a stop on the frame adapted to be engaged by said tabulator stop, means for rocking said shaft to move said tabulator stop into and out of operative alignment with said stop on the frame, a dash-pot mounted on said carriage and having means for permitting the gradual release of the cushioning medium, and connections between said dash-pot and said shaft whereby when the shaft is slid the dash-pot gradually arrests the carriage during its final extent of movement to its predetermined position.

2. In a machine of the class described, the combination of a frame, a laterally shiftable paper carriage, a shaft on said carriage, a plurality of tabulator stops thereon, a stop on the frame adapted to coact with the stops on the carriage to arrest movement of the latter, means for operating said shaft to move the stops thereon into and out of operative alignment with said stop on the frame, a dash-pot comprising a cylinder and a piston, one of which is mounted on the carriage, and connections between the other element of said dash-pot and said shaft and comprising a lever pivoted on the carriage and engaging a member on the shaft to gradually arrest the carriage as it moves to its predetermined position.

3. In a machine of the class described, the combination of a frame, a laterally shiftable paper carriage, a shaft slidably mounted on said carriage, a plurality of tabulator stops on said shaft, a stop on the

frame adapted to coact with said tabulating stops, means for rocking the shaft to move the stops thereon into and out of operative alignment with said stop on the carriage, a dash-pot comprising a cylinder and a piston, one of which is mounted on the carriage, and a lever between the other element of said dash-pot and said shaft whereby the dash-pot gradually arrests the carriage as it moves to its predetermined position.

4. In a machine of the class described, the combination of a frame, a laterally shiftable paper carriage, a shaft on said carriage, a plurality of tabulator stops on said shaft, a stop on the frame adapted to be abutted by the stops on said shaft to arrest movement of the carriage, means for operating the shaft to move the stops thereon into and out of operative alignment with the said stop on the frame, a dash-pot comprising a cylinder and a piston, one of which is mounted on the carriage, and connections between the other element of said dash-pot and said shaft constructed to cause the last-mentioned element of the dash-pot to move further than said carriage while the latter is being arrested in its predetermined position.

5. In a machine of the class described, the combination of a frame, a laterally shiftable paper carriage, a shaft slidably mounted on said carriage, a plurality of tabulator stops on said shaft, a stop on the frame adapted to coact with the stops on the carriage to arrest movement of the latter, means for rocking said shaft to move the stops thereon into and out of operative alignment with said stop on the frame, a dash-pot comprising a piston in the cylinder, one of which elements is mounted on the carriage, and connections between the other element of the dash-pot and said shaft constructed to cause said last-mentioned element of the dash-pot to move further than said carriage while the latter is being arrested.

6. In a machine of the class described, the combination of a laterally shiftable paper carriage, tabulator stop mechanism therefor comprising cooperating parts, a dash-pot, comprising a cylinder and piston, associated with said stop mechanism to act as a cushion for the carriage, one of said elements being fast on the carriage, and an operating connection between the other element of said dash-pot and one of said parts of said tabulating stop mechanism, for causing said last-mentioned element of the dash-pot to move further than said part while the carriage is being arrested.

7. In a machine of the class described, the combination of a frame, a laterally shiftable paper carriage thereon, a shaft on said carriage slidably mounted thereon and having an extension projecting from one side thereof, a part on said extension, a plurality

of tabulator stops on said shaft, a stop on the frame adapted to be engaged by the stops on said shaft to arrest movement of the carriage, means for rocking said shaft 5 to move the stops thereon into and out of operative alignment with said stop on the frame, a bracket secured to one side of said carriage, a dash-pot comprising a cylinder and a piston, one of which is fast to said

bracket, a lever pivoted on said bracket and secured to the other element of said dash-pot at one end and cooperating at its opposite end with said part on said extension, and a spring for rocking said lever and sliding said shaft when the cooperating stops 15 are disengaged.

FRANK C. RINSCHE.
